Primary Examiner — Rhea Shields

(57) **CLAIM**

The ornamental design for an electric connector, as shown and described.

DESCRIPTION

Electric connector

1.1 : Back

1.2 : Front

1.3 : Right

1.4 : Top

1.5 : Left

1.6 : Bottom

1.7 : Perspective

In the drawings, the broken lines are for the purpose of illustrating environment only and form no part of the claimed design.
